UNITED STATES PATENT OFFICE.

JOHN H. PATTERSON, OF DAYTON, OHIO, ASSIGNOR TO THE NATIONAL CASH REGISTER COMPANY, OF SAME PLACE.

CASH INDICATOR AND REGISTER.

SPECIFICATION forming part of Letters Patent No. 404,050, dated May 28, 1889.

Application filed June 1, 1888. Serial No. 275,765. (No model.)

To all whom it may concern:

Be it known that I, JOHN H. PATTERSON, a citizen of the United States, residing at Dayton, in the county of Montgomery and State of Ohio, have invented certain new and useful Improvements in Cash Registers and Indicators, of which the following is a full, clear, and exact description, reference being had to the accompanying drawings, forming part of this 10 specification.

My invention relates to an improvement in the construction of this class of machines, and its novelty will be herein set forth, and specifically pointed out in the claims.

15 In the accompanying drawings, Figure 1 is a plan view of one form of my improved machine. Fig. 2 is a side elevation of the same with the frame-work removed. Fig. 3 is a front perspective view looking at the machine 20 in the direction indicated by the arrow in Fig. 2. Figs. 4 and 5 are modifications to be referred to hereinafter.

The same letters of reference are used to indicate identical parts in all the figures.

25 My invention relates to that class of cash registers and indicators which employ a vibrating bar extending transversely across a series of keys and arranged to be actuated to different degrees by keys of different values, 30 and which bar in turn actuates a single registering-wheel to register the values of the operated keys. This bar may be a vertically-vibrating bar inclined relatively to the plane of the keys, such as is shown in Letters Patent No. 382,552, granted to me May 8, 1888; or it may be a vertically-vibrating bar having on its under side a series of steps or graduations arranged at different distances from the plane of the keys; or it may be a bar pivoted 35 at one side of and extending across the series of keys and arranged to be engaged by them at different distances from its pivotal point, all of which forms are well known in the art and are used for the same purpose.

45 This class of machines generally employ a series of keys indicating cents, in multiples of five, from 5 to 95, inclusive, which heretofore have been usually arranged to actuate a single registering-wheel bearing a series of 50 numbers in multiples of five, and arranged to

be turned one number for each multiple of five contained in the value of the actuated key. Thus the registering-wheel was turned one number by the operation of the five-cent key, two numbers by the ten-cent key, ten 55 numbers by the fifty-cent key, and so on up to the ninety-five-cent key, which turned the wheel nineteen numbers. Considerable difficulty has been experienced in causing the registering-wheel to stop at exactly the proper 60 point when one of the keys of higher value was actuated. Thus, if the ninety-five-cent key should be quickly or violently operated, the registering-wheel, in turning the nineteen 65 numbers necessary to register the value of that key, would acquire such momentum as would frequently carry it beyond the proper number, and thus cause an improper registration to be made. Different means have been employed to overcome this difficulty, 70 usually in the form of brake mechanism applied to the registering-wheel; but it is the object of my invention to more effectually overcome it by such an organization of the machine that it will not be necessary to turn 75 the registering-wheel so many numbers or so great a distance to register the value of any key, and this I accomplish by employing two wheels for registering the values of the cent-keys and combining them with the vibrating 80 bar and a five-cent bar which is arranged to cause the fives of the values of all the odd-numbered keys to be registered on one of said wheels, while the tens of their value are registered on the other, the values of the even-numbered keys being also registered on the latter wheel.

85 My improved machine is intended to be enclosed in the usual locked case or cabinet, provided in its upper portion with glass-covered reading-openings for the exposure of the indicating-tablets and in its lower front portion with openings through which project the forward ends of the usual operating-keys.

90 A is any suitable frame-work for supporting the operating parts of the machine; B, the keys, pivoted on a shaft, C, extending across the front of the frame-work, and carrying on their rear ends the usual vertical tablet-rods D, provided with shoulders E and ar- 95 100

ranged in guides F, and having at their upper ends the indicating-tablets G.

H is the vibrating resetting-frame, hung by its side arms, a, on the shaft C and extending across the tops of the keys in rear of said shaft.

I is the usual supporting-wing for the tablet-rods, and actuated by the vibrating frame H through the medium of the usual bell-10 crank lever, J, and tripping-dog b acting on the wiper-block c of the wing-extension d, and e f are the resetting-springs for the wing.

K is the usual gong-hammer, secured to the wing-extension d and arranged to strike 15 the gong L upon the resetting of the wing.

M N O are three registering-wheels strung upon a shaft, P, extending across the machine, and each provided with a ratchet containing, in this instance, one hundred teeth. The 20 wheel M, which I term the "five-cent-registering wheel," bears on its periphery five series of numbers, each indicating multiples of five from 0 to 95. The wheel N, or ten-cent wheel, bears on its periphery one series of numbers 25 indicating multiples of ten from 0 to 9.00, while the wheel O, or dollar-wheel, bears on its periphery one series of numbers in multiples of one from 0 to 99. The operating-keys B are arranged in two sets, those on the right 30 indicating cents in multiples of five from 5 to 95, inclusive, and those on the left dollars from 1 to 6, inclusive.

Hung upon the shaft C by side arms, g, is a bar, Q, extending transversely across 35 all of the cent-keys, excepting the five-cent key, in rear of their pivotal shaft C. The lower side of this bar, as seen in Fig. 3, is provided with a series of steps or graduations in inclined order downward from right 40 to left, each of said steps extending over two keys, one of which keys bears an odd number and the other the next lower even number. Upon depressing any key to its full extent this bar will be lifted, and it will be seen 45 that it will be actuated to different degrees by keys whose values contain different multiples of ten, while it will be actuated to the same extent by keys whose values contain the same multiple of ten. Thus the ten and 50 twenty cent keys will actuate it to different degrees, while the ten and fifteen cent keys will actuate it to the same degree, and so on through the series, each odd-numbered key actuating it to the same extent as does the 55 next lower even-numbered key.

Hung upon the shaft P by the side of the wheel N is a downwardly and rearwardly extending arm or dog carrier, R, carrying a spring-pressed dog, h, in constant engagement 60 with the ratchet of the wheel N. This arm R is connected by a link, S, to a rearwardly-extending lug, j, on the bar Q, and the adjustment of the parts is such that upon depressing any key to its full extent, and 65 thereby lifting the bar Q, the arm R will be lifted just far enough to cause its dog h to turn the wheel N a number of notches corre-

sponding to the number of tens in the value of the operated key, and upon releasing the key the bar Q and arm R will drop back to 70 their normal position of rest. Thus the operation of the ten and fifteen cent keys will each cause the wheel N to be turned one notch, the twenty and twenty-five cent keys two notches, and so on, the tens of the values 75 of all the keys, both odd and even numbered, being registered on the wheel N.

Hung upon the shaft C by side arms, k, is a five-cent bar, T, extending under all of the cent-keys in front of the shaft C, and provided with upwardly-extending projections l, one immediately beneath each of the odd-numbered keys. To a rearward extension, m, of one of the side arms of the bar T is pivoted a weighted dog, n, engaging with the 80 ratchet of the five-cent wheel. From this construction it will be seen that upon depressing any one of the even-numbered keys it will play between the projections on the bar T and the latter will not be moved; but 85 upon depressing any odd-numbered key it will engage the projection l immediately below it and depress the bar T, thereby actuating the dog n to turn the wheel M, and the adjustment of the parts is such that this operation of the bar T causes its dog to turn the wheel M just one notch, thereby registering five cents thereon. The tens of the value 90 of the operated key are simultaneously registered on the wheel N in the manner before 95 explained.

It will thus be seen that the operation of any odd-numbered key causes the wheel N to be turned less than half the distance required under the old construction, where it 100 registered both even and odd multiples of five and was turned one notch for each multiple of five contained in the value of the operated key. Thus under the old construction it would be turned nineteen notches by 105 the operation of the ninety-five-cent key, while under my improved construction it is turned only nine notches by the operation of said key. While I have shown the five-cent bar T as extending under the five-cent key, so 110 that the latter actuates the five-cent-registering wheel through the medium of said bar and its dog n, yet the five-cent key may, if desired, have pivoted to it a separate and independent dog engaging with the ratchet of 115 said wheel, in which event the bar T need not extend under said key.

An inclined bar, Q', hung on the shaft C by side arms, g', extends across the dollar-keys in rear of the shaft C, and is arranged to 120 actuate the wheel O through the medium of a dog-carrier, R', dog h', and connecting-link S', corresponding to those of the wheel N, as will be readily understood.

Spring-pressed holding-dogs o, secured to 130 lugs p on the upper guide-piece, F, engage one with the ratchet of each of the wheels M N O to prevent said wheels being turned backward and to act as brakes on their forward

movement, in addition to which dogs any of the usual forms of brake mechanism may, if desired, be applied to the wheels N and O.

The amounts registered by the revolutions 5 of the wheels M N O are taken off on supplemental registering-disks secured to the under side of a plate, U, Fig. 2, extending across the registering-wheels, one of said supplemental disks being arranged adjacent to the periphery of each registering-wheel and turned by a stud or pin projecting from said wheel, in the usual manner.

It will be understood that in the side elevation of the machine shown in Fig. 2 the dog 15 h on the arm R is in engagement with the ratchet of the wheel N, which is immediately behind the wheel M in said view, while the dog n of the five-cent bar engages with the ratchet of the wheel M.

20 While the bar Q, as shown in Fig. 3, and as thus far described, is provided on its lower side with a series of steps or graduations, with each of which an even-numbered and an odd-numbered key are arranged to engage, 25 for the purpose described, there are various other forms of said bar which may be employed for the same purpose. For instance, it may be an ordinary inclined bar—such as shown in my patent before referred to—and 30 the odd-numbered keys be slightly cut out or notched at their point of engagement with said bar; or, as seen in Fig. 4, the bar itself may be notched immediately above each odd-numbered key, or the keys might have their 35 upper edges beveled from one side and each odd-numbered key and the next lower even-numbered key be arranged close together, so that they would engage the lower edge of the bar Q at substantially the same point to actuate it to the same degree; or, again, as seen 40 in Fig. 5, the under side of the bar may be provided with two corresponding inclined surfaces, with one of which the group of even-numbered keys engage and with the other 45 the group of odd-numbered keys, and a bar of this form might be cut in two at its center to form two inclined bars instead of one bar with two inclines, in which event each of the portions would be connected to a common 50 dog-carrier carrying a dog engaging with the ratchet of the ten-cent-registering wheel, under either and all of which constructions each odd-numbered key and its next lower even-numbered key would actuate the bar to the 55 same extent, while it would be actuated to different degrees by different odd-numbered keys as well as by different even-numbered keys.

Again, while I have shown and described 60 my invention as applied to a machine employing a vertically-vibrating bar and pivoted keys, it is also applicable to machines embodying a horizontally-vibrating bar and horizontal pull-keys.

65 Having thus fully described my invention, I claim—

1. In a cash register and indicator, the com-

bination of a series of operating-keys indicating odd multiples of five above the first power, a ten-cent-registering wheel and a five-cent- 70 registering wheel, a bar extending transversely across said keys and arranged to be actuated to different degrees by the operation of different keys, connecting mechanism between said bar and the ten-cent-registering 75 wheel, a five-cent bar extending transversely across and arranged to be actuated to the same degree by all of said keys, and connecting mechanism between said five-cent bar and the five-cent-registering wheel, whereby upon 80 operating any one of said keys the tens of its value are registered on the ten-cent wheel and the five on the five-cent wheel, substantially as described.

2. In a cash register and indicator, the combination of a series of operating-keys indicating odd multiples of five above the first power, a ten-cent-registering wheel and a five-cent-registering wheel, each provided with a ratchet, a bar extending transversely across 90 said keys and arranged to be actuated to different degrees by the operation of different keys, a dog actuated by said bar and engaging with the ratchet of the ten-cent wheel, a five-cent bar extending transversely across 95 and arranged to be actuated to the same degree by all of said keys, and a dog actuated by said five-cent bar and engaging with the ratchet of the five-cent wheel, whereby upon 100 operating any one of said keys the tens of its value are registered on the ten-cent wheel and the five on the five-cent wheel, substantially as described.

3. In a cash register and indicator, the combination of a series of operating-keys indicating odd multiples of five above the first power, a ten-cent-registering wheel and a five-cent-registering wheel, a vertically-vibrating bar extending transversely across said keys and arranged to be actuated to different degrees 105 by the operation of different keys, connecting mechanism between said bar and the ten-cent-registering wheel, a five-cent bar extending transversely across and arranged to be actuated to the same degree by all of said keys, 110 and connecting mechanism between said five-cent bar and the five-cent-registering wheel, whereby upon operating any one of said keys the tens of its 115 value are registered on the ten-cent wheel and the five on the five-cent wheel, substantially as described.

4. In a cash register and indicator, the combination of a series of operating-keys indicating odd multiples of five above the first power, a ten-cent-registering wheel and a five-cent- 125 registering wheel, each provided with a ratchet, a vertically-vibrating bar extending transversely across said keys and arranged to be actuated to different degrees by the operation of different keys, a dog actuated by said 130 bar and engaging with the ratchet of the ten-cent wheel, a five-cent bar extending transversely across and arranged to be actuated to the same degree by all of said keys, and a

dog actuated by said five-cent bar and engaging with the ratchet of the five-cent wheel, whereby upon operating any one of said keys the tens of its value are registered on the ten-cent wheel and the five on the five-cent wheel, substantially as described.

5. In a cash register and indicator, the combination of a series of operating-keys indicating odd multiples of five above the first power, a ten-cent-registering wheel and a five-cent-registering wheel, a bar extending transversely across said keys and actuated thereby, the portions of said bar with which the different keys engage being arranged at different distances from said keys, connecting mechanism between said bar and the ten-cent-registering wheel, a five-cent bar extending transversely across and arranged to be actuated by all of said keys, and connecting mechanism between said five-cent bar and the five-cent-registering wheel, whereby upon operating any one of said keys the tens of its value are registered on the ten-cent wheel and the five on the five cent wheel, substantially as described.

25 6. In a cash register and indicator, the combination of a series of operating-keys indicating odd multiples of five above the first power, a ten-cent-registering wheel and a five-cent-registering wheel, each provided with a ratchet, a bar extending transversely across said keys and actuated thereby, the portions of said bar with which the different keys engage being arranged at different distances from said keys, a dog actuated by said bar and engaging with the ratchet of the ten-cent wheel, a five-cent bar extending transversely across and arranged to be actuated by all of said keys, and a dog actuated by said five-cent bar and engaging with the ratchet of the five-cent wheel, whereby upon operating any one of said keys the tens of its value are registered on the ten-cent wheel and the five on the five-cent wheel, substantially as described.

45 7. In a cash register and indicator, the combination of a series of operating-keys indicating odd multiples of five above the first power, a ten-cent-registering wheel and a five-cent-registering wheel, a bar extending transversely across and inclined relatively to the plane of said keys, connecting mechanism between said bar and ten-cent-registering wheel, a five-cent bar extending transversely across and actuated by all of said keys, and connecting mechanism between said five-cent bar and five-cent-registering wheel, whereby upon operating any one of said keys the tens of its value are registered on the ten-cent wheel and the five on the five-cent wheel, substantially as described.

60 8. In a cash register and indicator, the combination of a series of operating-keys indicating odd multiples of five above the first power, a ten-cent-registering wheel and a five-cent-registering wheel, each provided with a ratchet, a bar extending transversely across and inclined relatively to the plane of said

keys, a dog actuated by said bar and engaging with the ratchet of the ten-cent-registering wheel, a five-cent bar extending transversely across and actuated by all of said keys, and a dog actuated by said five-cent bar and engaging with the ratchet of the five-cent-registering wheel, whereby upon operating any one of said keys the tens of its value are registered on the ten-cent wheel and the five on the five-cent wheel, substantially as described.

9. In a cash register and indicator, the combination of a series of operating-keys indicating even and odd multiples of five above the first power, a ten-cent-registering wheel and a five-cent-registering wheel, a bar extending transversely across said keys and arranged to be actuated to different degrees by the different odd-numbered keys and to different degrees by the different even-numbered keys, but to the same degree by each odd-numbered key and the next lower even-numbered key, connecting mechanism between said bar and the ten-cent-registering wheel, a five-cent bar extending transversely across and arranged to be actuated by each odd-numbered key, and connecting mechanism between said five-cent bar and the five-cent-registering wheel, whereby upon operating an even-numbered key its value is registered on the ten-cent wheel, and whereby upon operating an odd-numbered key the tens of its value are registered on the ten-cent wheel and the five on the five-cent wheel, substantially as described.

10. In a cash register and indicator, the combination of a series of operating-keys indicating even and odd multiples of five above the first power, a ten-cent-registering wheel and a five-cent-registering wheel, each provided with a ratchet, a bar extending transversely across said keys and arranged to be actuated to different degrees by the different odd-numbered keys and to different degrees by the different even-numbered keys, but to the same degree by each odd-numbered key and the next lower even-numbered key, a dog actuated by said bar and engaging with the ratchet of the ten-cent-registering wheel, a five-cent bar extending transversely across and arranged to be actuated by each of the odd-numbered keys, and a dog actuated by said five-cent bar and engaging with the ratchet of the five-cent-registering wheels, whereby upon operating an even-numbered key its value is registered on the ten-cent wheel, and whereby upon operating an odd-numbered key the tens of its value are registered on the ten-cent wheel and the five on the five-cent wheel, substantially as described.

11. In a cash register and indicator, the combination of a series of operating-keys indicating even and odd multiples of five above the first power, a ten-cent-registering wheel and a five-cent-registering wheel, a vertically-vibrating bar extending transversely across said keys and arranged to be actuated to different degrees by the different odd-numbered

keys and to different degrees by the different even-numbered keys, but to the same degree by each odd-numbered key and the lower even-numbered key, connecting mechanism 5 between said bar and the ten-cent-registering wheel, a five-cent bar extending transversely across and arranged to be actuated by each of the odd-numbered keys, and connecting mechanism between said five-cent bar and 10 five-cent-registering wheel, whereby upon operating an even-numbered key its value is registered on the ten-cent wheel, and whereby upon operating an odd-numbered key the tens of its value are registered on the ten-cent wheel and the five on the five-cent wheel, substantially as described.

12. In a cash register and indicator, the combination of a series of operating-keys indicating even and odd multiples of five above 20 the first power, a ten-cent-registering wheel and a five-cent-registering wheel, each provided with a ratchet, a vertically-vibrating bar extending transversely across said keys and arranged to be actuated to different degrees 25 by the different odd-numbered keys and to different degrees by the different even-numbered keys, but to the same degree by each odd-numbered key and the next lower even-numbered key, a dog actuated by said 30 bar and engaging with the ratchet of the ten-cent wheel, a five-cent bar extending transversely across and arranged to be actuated by each odd-numbered key, and a dog actuated by said five-cent bar and engaging with the 35 ratchet of the five-cent-registering wheel, whereby upon operating an even-numbered key its value is registered on the ten-cent wheel, and whereby upon operating an odd-numbered key the tens of its value are registered on the ten-cent wheel and the five on the five-cent wheel, substantially as described.

13. In a cash register and indicator, the combination of a series of operating-keys indicating even and odd multiples of five above 45 the first power, a ten-cent-registering wheel and a five-cent-registering wheel, a bar extending transversely across said keys and actuated thereby, the portions of said bar with which the different odd-numbered keys 50 engage being arranged at different distances from said odd-numbered keys and the portions with which the different even-numbered keys engage being arranged at different distances from said even-numbered keys, but the portions with which each odd-numbered key and 55 the next lower even-numbered key engage being arranged at the same distance from said keys, connecting mechanism between said bar and the ten-cent-registering wheel, a 60 five-cent bar extending transversely across and arranged to be actuated by each of the odd-numbered keys, and connecting mechanism between said five-cent bar and the five-cent-registering wheel, whereby upon operating an even-numbered key its value is registered on the ten-cent wheel, and whereby upon operating an odd-numbered key the tens of its value are registered on the ten-cent wheel and the five on the five-cent wheel, substantially as described.

65 14. In a cash register and indicator, the combination of a series of operating-keys indicating even and odd multiples of five above the first power, a ten-cent-registering wheel and a five-cent-registering wheel, each provided with a ratchet, a bar extending transversely across and inclined relatively to the plane of said keys and arranged to be actuated to different degrees by the different odd-numbered keys and to different 70 degrees by the different even-numbered keys, but to the same degree by each odd-numbered key and the next lower even-numbered key, connecting mechanism between said bar and the ten-cent-registering wheel, a five-cent bar extending transversely across and actuated by each odd-numbered key, and connecting mechanism between said five-cent bar and the five-cent-registering wheel, whereby upon operating an even-numbered key its value is registered on the ten-cent wheel, and whereby upon operating an odd-numbered key the tens of its value are registered on the ten-cent wheel and the five on the five-cent wheel, substantially as described.

tens of its value are registered on the ten-cent wheel and the five on the five-cent wheel, substantially as described.

15. In a cash register and indicator, the combination of a series of operating-keys indicating even and odd multiples of five above the first power, a ten-cent-registering wheel and a five-cent-registering wheel, each provided with a ratchet, a bar extending transversely across said keys and actuated thereby, the portions of said bar with which the different odd-numbered keys engage being arranged at different distances from said odd-numbered keys and the portions with which the different even-numbered keys engage being arranged at different distances from said even-numbered keys, but the portions with which each odd-numbered key and the next 80 lower even-numbered key engage being arranged at the same distance from said keys, a dog actuated by said bar and engaging with the ratchet of the ten-cent-registering wheel, a five-cent bar extending transversely 90 across and arranged to be actuated by each of the odd-numbered keys, and a dog actuated by said five-cent bar and engaging with the ratchet of the five-cent-registering wheel, whereby upon operating an even-numbered key its value is registered on the ten-cent wheel, and whereby upon operating an odd-numbered key the tens of its value are registered on the ten-cent wheel and the five on the five-cent wheel, substantially as described.

16. In a cash register and indicator, the combination of a series of operating-keys indicating even and odd multiples of five above the first power, a ten-cent-registering wheel and a five-cent-registering wheel, a bar extending transversely across and inclined relatively to the plane of said keys and arranged to be actuated to different degrees by the different odd-numbered keys and to different 100 degrees by the different even-numbered keys, but to the same degree by each odd-numbered key and the next lower even-numbered key, connecting mechanism between said bar and the ten-cent-registering wheel, a five-cent bar extending transversely across and actuated by each odd-numbered key, and connecting mechanism between said five-cent bar and the five-cent-registering wheel, whereby upon operating an even-numbered key its value is registered on the ten-cent wheel, and whereby upon operating an odd-numbered key the tens of its value are registered on the ten-cent wheel and the five on the five-cent wheel, substantially as described.

17. In a cash register and indicator, the combination of a series of operating-keys indicating even and odd multiples of five above the first power, a ten-cent-registering wheel and a five-cent-registering wheel, each provided with a ratchet, a bar extending transversely across and inclined relatively to the plane of said keys and arranged to be actuated to different degrees by the different odd-numbered keys and to different 110 degrees by the different even-numbered keys, but to the same degree by each odd-numbered key and the next lower even-numbered key, connecting mechanism between said bar and the ten-cent-registering wheel, a five-cent bar extending transversely across and actuated by each odd-numbered key, and connecting mechanism between said five-cent bar and the five-cent-registering wheel, whereby upon operating an even-numbered key its value is registered on the ten-cent wheel, and whereby upon operating an odd-numbered key the tens of its value are registered on the ten-cent wheel and the five on the five-cent wheel, substantially as described.

odd-numbered keys and to different degrees by the different even-numbered keys, but to the same degree by each odd-numbered key and the next lower even-numbered key, a dog actuated by said bar and engaging with the ratchet of the ten-cent-registering wheel, a five-cent bar extending transversely across and actuated by each of the odd-numbered keys, and a dog actuated by said five-cent bar and engaging with the ratchet of the five-cent-registering wheel, whereby upon operating an even-numbered key its value is registered on the ten-cent wheel, and whereby upon operating an odd-numbered key the tens of its value are registered on the ten-cent wheel and the five on the five-cent wheel, substantially as described.

17. In a cash register and indicator, the combination of a series of operating-keys indicating even and odd multiples of five above the first power, a series of tablet-rods and indicating-tablets actuated by said keys, a ten-cent-registering wheel and a five-cent-registering wheel, each provided with a ratchet, a bar extending transversely across said keys and arranged to be actuated to different degrees by the different odd-numbered keys and to different degrees by the different even-numbered keys, but to the same degree by each odd-numbered key and the next lower even-numbered key, a dog actuated by said bar and engaging with the ratchet of the ten-cent-registering wheel, a five-cent bar extending transversely across and arranged to be actuated by each of the odd-numbered keys, and a dog actuated by said five-cent bar and engaging with the ratchet of the five-cent-registering wheel, substantially as and for the purpose described.

18. In a cash register and indicator, the combination of a series of operating-keys indicating even and odd multiples of five above the first power, a series of tablet-rods and indicating-tablets actuated by said keys, a ten-cent-registering wheel and a five-cent-registering wheel, each provided with a ratchet, a vertically-vibrating bar extending transversely across said key and arranged to be actuated to different degrees by the different odd-numbered keys and to different degrees by the different even-numbered keys, but to the same degree by each odd-numbered key and the next lower even-numbered key, a dog actuated by said bar and engaging with the ratchet of the ten-cent wheel, a five-cent bar extending transversely across and arranged to be actuated by each odd-numbered key, and a dog actuated by said bar and engaging with the ratchet of the ten-cent wheel, a five-cent bar extending trans-

versely across and arranged to be actuated by each of the odd-numbered keys, and a dog actuated by said five-cent bar and engaging with the ratchet of the five-cent-registering wheel, substantially as and for the purpose 65 described.

19. In a cash register and indicator, the combination of a series of operating-keys indicating even and odd multiples of five above the first power, a series of tablet-rods and indicating-tablets actuated by said keys, a ten-cent-registering wheel and a five-cent-registering wheel, each provided with a ratchet, a bar extending transversely across said keys and actuated thereby, the portions 75 of said bar with which the different odd-numbered keys engage being arranged at different distances from said odd-numbered keys and the portions with which the different even-numbered keys engage being arranged 80 at different distances from said even-numbered keys, but the portions with which each odd-numbered key and the next lower even-numbered key engage being arranged at the same distance from said keys, a dog 85 actuated by said bar and engaging with the ratchet of the ten-cent-registering wheel, a five-cent bar extending transversely across and arranged to be actuated by each odd-numbered key, and a dog actuated by said 90 five-cent bar and engaging with the ratchet of the five-cent-registering wheel, substantially as and for the purpose described.

20. In a cash register and indicator, the combination of a series of operating-keys indicating even and odd multiples of five above the first power, a series of tablet-rods and indicating-tablets actuated by said keys, a ten-cent-registering wheel and a five-cent-registering wheel, each provided with a ratchet, a bar extending transversely across and inclined relatively to the plane of said keys and arranged to be actuated to different degrees by the different odd-numbered keys and to different degrees by the different even-numbered keys, but to the same degree by each odd-numbered key and the next lower even-numbered key, a dog actuated by said bar and engaging with the ratchet of the ten-cent-registering wheel, a five-cent bar 105 extending transversely across and actuated by each of the odd-numbered keys, and a dog actuated by said five-cent bar and engaging with the ratchet of the five-cent-registering wheel, substantially as and for the purpose 110 described.

JOHN H. PATTERSON.
